UNITED STATES PATENT OFFICE.

HORACE W. BEEBE, OF NEW HAVEN, CONNECTICUT.

VEHICLE-LAMP.

969,445.

Specification of Letters Patent. Patented Sept. 6, 1910.

Application filed May 2, 1910. Serial No. 558,959.

To all whom it may concern:

Be it known that I, HORACE W. BEEBE, a citizen of the United States, residing at New Haven, in the county of New Haven and State of Connecticut, have invented a new and useful Improvement in Vehicle-Lamps; and I do hereby declare the following, when taken in connection with the accompanying drawings and the letters of reference marked thereon, to be a full, clear, and exact description of the same, and which said drawings constitute part of this specification, and represent, in—

Figure 1 a front view of a vehicle lamp embodying my invention with the burner broken away. Fig. 2 a side view partially in section of the lamp showing the disks spread, and also indicated by broken lines as in the retired position. Fig. 3 a broken top or plan view showing the disks in their retired position. Fig. 4 an enlarged sectional view of the lower portion of the tube showing means for operating the rod. Fig. 5 a sectional view on the line *a—b* of Fig. 4.

This invention relates to an improvement in vehicle lamps, and particularly to lamps in which a "dimmer" is arranged between the burner and reflector, and adapted to be spread so as to temporarily suppress the action of the reflector, and is an improvement on the invention shown and described in Letters Patent No. 925,676. In the construction shown and described in the above patent, a spring was required to hold the parts of the disk in an open position.

The object of this invention is to provide the tube in which the dimmer slides with a cam groove, and the dimmer with fingers to engage with the edges of the groove so that the dimmer will be positively opened, and the invention consists in special means for operating the dimmer as will be more fully hereinafter described and particularly recited in the claims.

In carrying out my invention I employ a lamp body 2 of usual construction including a fixed reflector 3 and a burner 4. In rear of the burner 4 is a tube 5 which projects down through the bottom of the lamp. The rear of the tube 5 is cut away forming cam surfaces 6 and 7, while in the front of the tube is a slot 8 forming curved cam surfaces 9 and 10. Within the tube is a vertically movable rod 11, and hinged to this rod are two semi-circular leaves 12 and 13 like the leaves in the patent before men-

tioned. Secured to the forward face of each leaf is a finger 14 and 14^a, which fingers enter the slot 8 and ride over the cam surfaces 9 and 10 and so that as the rod is raised, the leaves will be spread, as shown in Fig. 1 of the drawings; and when the rod is depressed these fingers riding in the grooves will cause the leaves to be folded as shown in Fig. 3 of the drawings. The rod 11 is made larger at its lower end than at the upper end to which the leaves are attached, the main portion of the rod closely fitting the tube 5 and giving sufficient weight to cause the rod to normally remain in its lower position and so that the leaves will be normally held in a folded position. As a matter of convenience the portion 16 of the tube which projects below the lamp casing will be made separate from the upper portion 15, and the parts will be threaded together so that they will be separated. The upper part will be provided with a flange 17 which rests upon the bottom of the inside of the casing, and the lower part of the tube will therefore hold and clamp the upper part in place.

Formed as a part of, or secured to the upper part of the lower portion 16 of the tube is a housing 18 carrying a roller 19 over which a cord or wire 20 will pass into engagement with the lower end of the rod 11 and so that a pull upon this cord or wire 20 will lift the rod 6 and cause the disks to open. When this cord or wire is released the rod will fall by gravity and thus fold the leaves. This cord or wire 20 may lead through a pipe 21 or otherwise to any point in the vehicle convenient to the operator. If a pipe is employed the pipe 21 will lead to a cylinder 22 in which a slide 23 is arranged, this slide being connected to the end of the wire or cord 20 and in the cylinder I arrange a spiral spring 24, the tendency of which is to draw the slide downward. This cylinder is preferably arranged adjacent to the steering post and a convenient handle connected with the slide so it may be pulled upward, this pull upward lifting the rod 11 so as to spread the dimmer. When it is released the spring 24 will act to draw back the slide 23 so that the rod 11 may by its own weight drop in the tube and fold the dimmer.

As in the patent before referred to, the disks are spread between the burner and reflector whenever it is desirable to tem-

porarily suppress the action of the reflector as when two vehicles are approaching each other. To spread the reflector it is only necessary to pull upon the wire or cord 20, 5 and then when the necessity of suppressing the action of the reflector is passed, releasing the wire or cord will allow the rod to drop and draw the disks into their retired position, a 10 position in a line directly behind the burner so that no shadow is caused by them.

I claim:

1. In a lamp, the combination with the burner and reflector, of a tube located between the burner and reflector, said tube being formed with a slot in its front face extending downward on opposite sides, a vertically movable rod in said tube, and two semi-circular disks hinged to said rod, said disks being provided with fingers projecting into said slot. 20

2. In a lamp, the combination with a burner and reflector, of a tube located between the burner and reflector, said tube formed on its rear face with cam-surfaces 25 and with a groove at the front extending down on opposite sides also forming cam surfaces, a vertically movable rod in said

tube, two semi-circular disks hinged to said rod and provided with fingers extending into said groove, a roller mounted adjacent to the tube below the lamp, and a wire or cord passing over said roller and secured to the lower end of said tube whereby said tube may be raised. 3

3. In a lamp, the combination with a burner and reflector, of a tube located between the burner and reflector, a rod mounted in said tube, semi-circular disks hinged to said rod and adapted to be spread above the burner, a cord secured to the lower end of said rod, a pipe through which said cord extends, a cylinder at the outer end of said pipe, a slide in said cylinder and connected with said cord, and a spring in said cylinder and tending to draw the slide into the cylinder. 4

In testimony whereof, I have signed this specification in the presence of two subscribing witnesses.

H. W. BEEBE.
